(57) **CLAIM**

I claim the ornamental design for a watering hose nozzle, as shown and described.

DESCRIPTION

FIG. 1 is a side view of the watering hose nozzle showing my design, wherein an opposite side view is a mirror image thereof, wherein a top view is a mirror image thereof, and wherein a bottom view is a mirror image thereof;

FIG. 2 is an end view thereof; and,

FIG. 3 is an opposite end view thereof.
